UNITED STATES PATENT OFFICE.

BENHARD JOHNSON, OF BOSTON, MASSACHUSETTS.

DESIGN FOR A SHOE-LACE FASTENING.

SPECIFICATION forming part of Design No. 28,793, dated June 7, 1898.

Application filed May 5, 1898. Serial No. 679,855. Term of patent 14 years.

To all whom it may concern:

Be it known that I, BENHARD JOHNSON, a citizen of the United States, residing in Boston, in the county of Suffolk and State of Massachusetts, have invented and produced a new and original Design for Shoe-Lace Fastenings, of which the following description, in connection with the accompanying drawings, is a specification, like letters on the drawings representing like parts.

The design relates to a shoe-lace fastening; and it consists of a fastening distinguished by its peculiar shape, as will be hereinafter set forth and claimed.

The leading and distinguishing feature of this invention consists in a shoe-lace fastening of the shape or configuration shown, and consists of a continuous wire having the substantially straight vertical portion or end a , from which the side a' extends substantially at right angles thereto and which is joined by the cross-piece a^2 to the side a^3 , occupying substantially the same plane as the side a' , and from the end of which extends back toward the cross-piece a^2 , between the sides a' a^3 , the portion or length a^4 , which lies in substantially the same plane as the sides a' a^3 , and from which extends the straight end portion a^5 .

I claim—

The design for a shoe-lace fastening herein shown and described.

In testimony whereof I have signed my name to this specification in the presence of two subscribing witnesses.

BENHARD JOHNSON.
